—INVENTOR:—

Joseph Bevan.

BY Drake & Co. ATT'YS.

UNITED STATES PATENT OFFICE.

JOSEPH BEVAN, OF NEWARK, NEW JERSEY.

DESIGN FOR A SADDLE-TREE.

SPECIFICATION forming part of Design No. 16,977, dated November 9, 1886.

Application filed August 20, 1886. Serial No. 211,443. Term of patent 14 years.

To all whom it may concern:

Be it known that I, JOSEPH BEVAN, a citizen of the United States, residing at Newark, in the county of Essex and State of New Jersey, have invented and produced a new and original Design for Saddle-Trees; and I do hereby declare the following to be a full, clear, and exact description of the invention, such as will enable others skilled in the art to which it appertains to make and use the same, reference being had to the accompanying drawing, and to letters of reference marked thereon, which form a part of this specification.

The figure is a slightly perspective side elevation of a newly designed saddle tree, the one view being considered sufficient to show the design.

The leading feature of the design consists in a saddle-tree having the peculiar configuration hereinafter set forth, and finally embodied in the clause of the claim.

In said drawing, *a* indicates the pommel, the front edge, *b*, of which, when viewed in side elevation, presents a straight vertical outline, which extends to a "burr," *c*, where the said outline is rounded outwardly or forwardly and downwardly, as at *d*, an angle being formed at *c*, where the vertical and outwardly curved lines join or come together. The outline then curves backwardly at *f* and upwardly at *g*, approaching at this point, when viewed in side elevation, nearly a vertical line, and at *h* again curves backwardly and slightly downwardly to *i* near the back of the tree, where it gives another upward turn at *j*, and finally a forward turn, as at *k*, terminating beneath the cantle, the line which forms an angle with the front edge of the pommel being a continuous compound curve from the said angle to the point *k*. This description applies, as will be understood, to one side of the saddle, the other being of like shape. The upper edge of the cantle curves upwardly and backwardly, as at *m*, then rounding, as at *q*, and, curving forwardly, joins the regular curve at a point opposite *m*, the shape of the cantle at the upper and backward extremity, *q*, resembling a tongue-shaped protuberance.

The edge *n* at the center slot, *o*, of the saddle-tree, when viewed in side elevation, presents at a point just back of the pommel a curve or an incline downward from said pommel which is nearly parallel with the line *p* at the top of said pommel.

The top or middle of the upper portion of the pommel, when viewed in side elevation, presents to view the inclined surface *p*, above referred to, which is shown to incline backwardly and downwardly from the vertical line *b* to the forward end of the slot *o*, and does not rise and project forward in giving outline to a horn, as in other saddles of which I am aware.

I am aware that individually the several lines of configuration above referred to are old; but, combining them as shown and described, a saddle-tree of a distinctive appearance and of peculiar beauty of outline is obtained.

I claim—

The design for a saddle-tree herein described, which consists, essentially, in a saddle-tree having at the top of the pommel the inclined line *p*, which extends to the end of the slot *o*, the vertical line *b* at the front of the pommel terminating at the line *d* and forming an angle therewith, said line *d* curving forwardly and downwardly, then backwardly and downwardly, as at *f*, then upwardly, as at *g*, then downwardly, as at *h*, then upwardly, as at *j*, then forwardly, as at *k*, to the cantle, and the upper or edge line of the cantle curving backwardly and upwardly, then backwardly or outwardly, as at *m*, then rounding, as at *q*, and curving again forwardly, joining the regular curve at a point opposite *m*, the shape of the cantle at the upper and backward extremity, *q*, resembling a tongue-shaped protuberance, as described and shown.

In testimony that I claim the foregoing I have hereunto set my hand this 19th day of August, 1886.

JOSEPH BEVAN.
